UNITED STATES PATENT OFFICE

138,853

DESIGN FOR A PREFORMED NECKTIE

Alfred Frank Taborski, Buffalo, N. Y.

Application June 29, 1944, Serial No. 114,248

Term of patent 7 years

(Cl. D3—16)

To all whom it may concern:

Be it known that I, Alfred F. Taborski, a citizen of the United States, residing at Buffalo, in the county of Erie and State of New York, have invented a new, original, and ornamental Design for a Preformed Necktie, of which the following is a specification, reference being had to the accompanying drawing, forming a part thereof.

I claim:

The ornamental design for a preformed necktie, as shown.

ALFRED FRANK TABORSKI.
